UNITED STATES PATENT OFFICE

JOHN J. BROSNAN, OF WORCESTER, MASSACHUSETTS

STRONG BOX

Application filed June 11, 1931. Serial No. 543,646.

This invention relates to a strong box adapted to be exposed in public places for the reception of coins and the like.

The principal objects of the invention are to provide a very strong construction which cannot be opened by amateur methods at least; to provide a false bottom constituting in itself a lock for the removable outer casting to make drilling into the bottom more difficult and to add in other respects to the difficulty of getting into the inside of the box and also constituting means whereby, if a would-be thief does break through the false bottom, he will think that he has reached the inside of the strong box and very likely will not attempt to go further; to provide means for locking the false bottom in its projecting position where it locks the outside cover; to provide means for positively preventing the false bottom from being retracted, said means being controlled by a lock; to provide means whereby if this lock should be broken in any way the locking means for the false bottom will still act; and in short to provide a safe, durable and relatively inexpensive construction.

Other objects and advantages of the invention will be described hereinafter.

Reference is to be had to the accompanying drawings, in which

Fig. 1 is a perspective view of a strong box constructed in accordance with this invention and shown closed and in working condition;

Fig. 2 is a front elevation of the inside of the strong box, the cover being removed;

Fig. 3 is a plan of the same;

Fig. 4 is a rear elevation of the base which is adapted to be secured to a vertical wall, or the like;

Fig. 5 is a sectional view on the line 5—5 of Figs. 1 and 4, and

Fig. 6 is a sectional view on the line 6—6 of Fig. 4.

This strong box is intended for general purposes, but is particularly adapted for church boxes for the reception of offerings for various purposes.

The box preferably is made up of a strong base 10. It is preferred to make this base of

malleable iron which can be made so strong that it is practically impossible to break it or seriously injure it by any ordinary means. The base embodies a flat plate which is provided with bosses 11, all perforated to receive bolts by which it can be secured in place against a wall or the like. It is also provided with an integral wall 12 extending across it reaching to the plane of a surrounding flange 13 which is integral with it and which is the part which rests against the wall. 55 60

On the inside of the base are one or more perforated bosses 14, through which bolts 15 can be inserted to secure to the front of this base an inside casing 16. This casing is located within a three walled flange 17 integral with the base and extending up from it all around so that tools cannot be introduced between the casing and the base. This inside casing consists of a back wall and two side 70 walls, and it has a pair of parallel flanges 18 in one plane at the bottom on the sides and a rear flange of a similar character and in the same plane projecting inwardly. The casing also has a bottom 19 welded or otherwise 75 firmly secured to it, this bottom having a flange extending around it below it by which it is riveted preferably to the casing. It is elevated above the actual bottom of the casing sufficiently to receive a false bottom 20 80 below it. The casing 16 also has a chute 21 extending in at an inclination from the top over which the coins slide into it. The casing 16 with all the parts just described, is made of strong sheet steel. 85

The false bottom 20 is made of a sheet steel stamping of a materially heavier grade and can be made of a metal which will be very difficult to penetrate either by saw or drill. It has four flanges integral with each other 90 at the corners and at the bottom, turning down from it and filling the space between the bottom of the flanges on the permanent bottom and the flanges 18. The top of this false bottom is depressed so that a few coins may be placed in it. This is for the purpose of deceiving any would-be robber, that penetrated it, into thinking that he has actually gotten into the strong box and that it is practically empty. It will be understood that it slides 95 100

in over the flanges 18 which support it and extends from the front to the back of the casing 16.

An outer casing or cover 23 is made of some heavy and relatively strong metal, such as chromium steel or the like, and is preferably of a rectangular form having smooth sides and top, the latter having a coin receiving slot 24 which, of course, when the parts are in position, will be located over the chute 21. It is also provided with two flanges 25 extending inwardly in the same plane from the opposite sides to project through spaces 26 between the casing 16 and the top of the base 10 which is raised. This holds the cover on the base from one end to the other in this way.

At the bottom on the inner side of the front face of the outer casing is located a piece 27 of metal of the same kind having flanges at the top and bottom, the upper flange 28 being adapted to come against the top edge of the false bottom, and the lower flange 29 coming under the lower edge of the false bottom. Thus when the false bottom is projected against the front it comes against this flange 29 and locks the cover to the casing. The bottom of the cover is all open except for this flange.

The method of operating the false bottom is to provide one or more lugs 30 integral with the base 10 and perforated throughout their length to receive a corresponding number of plungers 31. Springs 45 are provided for normally forcing said plungers forwardly. The plungers project into the space behind the false bottom so as to hold that outwardly in locking position by spring pressure. These plungers project beyond the spring backwardly and a plate 32 is provided having rods 33 fixed thereto which are normally pressed by a spring 34 through openings in the lugs 30 and into the passages therein to limit the backward motion of these plungers 31. Therefore when the spring 34 is forced to hold the plate in the position shown in Fig. 4, the false bottom is positively locked in a position to lock the cover on the casing. The spring 34 is mounted on a plunger 35 guided in a part of the wall 12 and in another integral lug 36 on the base to move in a straight line, and the spring 34 presses on the wall 12 to keep the device locked whenever it is free to move.

Guided in a projection on the wall 12 is a bolt 37 constituting a feature of an ordinary pin-and-tumbler or disc lock 38. A key 39 can be inserted in this lock, preferably from either side of the base 10, to turn this bolt 37. The bolt has a cam 40 adapted to engage, during its rotation, a projection 41 on the plunger 35 to draw back the plunger, and with it the plate 32 which is located on the end of this plunger. This withdraws the plungers 33 from the passages 42. Now, these passages being unobstructed, the false

bottom can be forced back by placing the fingers in from the bottom and pressing on the side toward the back, and this will release the cover. The cover, of course, can be removed and the coins taken out. If desired a coin box 43 can be mounted loosely on the fixed bottom 19 for receiving coins and adapted to be taken out to empty them.

In this way it will be seen that a very strong construction is provided which will have means for deceiving a would-be robber if he tries to get into the bottom, so that, if he succeeds in picking the lock 38, nothing will indicate to a stranger how the box can be opened. The springs which hold the false bottom in its extended locking position are strong enough so that it will not move unless the party presses it in with considerable force, and there is nothing about it to indicate that it can be pressed in. Furthermore, the base is made of such material that it is practically impossible to injure it and it cannot be broken by blows of a sledge hammer. Also the cover, as stated, is of very resistant metal and so is the false bottom. In other words, all the parts that are exposed when the box is in use are extremely difficult to tamper with. This constitutes a very safe type of strong box, particularly adapted for exposure in public places where coins are deposited by the public.

Although I have illustrated and described only one form of the invention I am aware of the fact that changes can be made therein by any person skilled in the art without departing from the scope of the invention as expressed in the claims. Therefore I do not wish to be limited to the exact form shown, but what I do claim is:—

1. In a strong box, the combination of a base having an integral flange around it at the back to fit against a wall or the like and means for securing said base to said wall, of an inner casing secured to said base on the front, an outer casing slidable over said inner casing, a member closing the bottom of the inner casing and adapted to engage the outer casing to lock it in closed position, and means within the area of the flanges of the base for controlling said locking member. 110

2. In a strong box, the combination of a strong base and means for securing it against a wall, of an inner casing, means for securing the inner casing to the base, an outer casing adapted to enclose the inner casing, said inner casing having a permanent bottom spaced from the lower end thereof and extending throughout the entire area of said casing near the bottom, a false bottom below the permanent bottom, an outer casing having an inner projection which the false bottom is adapted to engage to lock the outer casing to the inner casing and means contained in and concealed by the base for controlling the action of said false bottom. 120

3. In a strong box, the combination of a base having a flange projecting from the face thereof around three sides on the front and means for securing said base to a wall or the like, of an inner casing located within the flange, means for securing the inner casing to the base, an outer casing slideable over the inner casing, a false bottom slidably located in the bottom of the inner casing and having means whereby, when the false bottom is projected outwardly, it will lock the outer casing in position, positive means for preventing the false bottom from being retracted from its locking position, and key-operated means for withdrawing said positive means.

4. In a strong box, the combination of a strong, durable base of malleable iron having a flange projecting from the face thereof around three sides on the front and means for securing said base to a wall or the like, of an inner casing of sheet metal located within the flange so as to prevent access to the back of the inner casing, means for securing the inner casing to the base and spacing the edges of the back of it therefrom, an outer casing of strong, tough metal, slideable over the inner casing and having longitudinal flanges at its opposite sides adapted to project into said spaces, a false bottom of hard tough metal slidably located in the bottom of the inner casing and having means whereby, when the false bottom is projected outwardly, it will lock the outer casing in position, yielding means for forcing the false bottom into locking position, positive means concealed by said base for preventing the false bottom from being retracted from its locking position, and key-operated means for withdrawing said positive means.

5. In a strong box, the combination of a base, an inner casing and an outer casing, the outer casing having an inward projection at the end, a false bottom transversely slideable in the bottom of the inner casing into engagement with said projection for the purpose of locking the outer casing thereto, and releasable means to hold the false bottom positively in locking position, whereby the false bottom, which is accessible from below, can be forced in to unlock the outer casing.

6. In a strong box, the combination of a base, an inner casing and an outer casing, the outer casing having an inward projection at the end, a false bottom transversely slideable in the bottom of the inner casing into engagement with said projection for the purpose of locking the outer casing thereto, a spring-pressed plunger for forcing the false bottom into locking position, said plunger being supported by the base which is provided with an opening for receiving it, a second plunger adapted to move across said opening to engage the end of the plunger and hold the false bottom positively in locking position, whereby when the second plunger

is withdrawn, the false bottom, which is accessible from below, can be forced in to unlock the outer casing.

7. In a strong box, the combination of two parts movably connected together, constituting a strong box proper, a member at the bottom of one of said parts loosely mounted and adapted when projected to lock the two parts together, a spring-pressed plunger for forcing the said member into locking position, means for engaging the end of said plunger to positively prevent the retraction of said movable part, yielding means for forcing the last named means into its positive locking position and key-operated means for pulling it out of its locking position.

In testimony whereof I have hereunto affixed my signature.

JOHN J. BROSNAN.
